UNITED STATES PATENT OFFICE.

CHARLES A. WULF, OF INDIANAPOLIS, INDIANA, ASSIGNOR TO AMERICAN VALVE AND ENAMELING CORPORATION, OF INDIANAPOLIS, INDIANA, A CORPORATION OF INDIANA.

TOILET FLUSHING MECHANISM.

Original application filed August 20, 1925, Serial No. 51,296. Divided and this application filed November 13, 1925. Serial No. 68,827.

The object of my invention is to provide an improved flushing-valve structure for toilet flushing tanks. This application is a division from my co-pending application Serial No. 51,296.

The accompanying drawings illustrate my invention.

Fig. 1 is an elevation, in partial vertical section, of my structure arranged in 10 place in a flushing tank;

Fig. 2 an elevation of the manipulator and dash pot, in a plane at right angles to that of Fig. 1, on a larger scale; Fig. 3 an elevation, in the plane of Fig. 1 of the 15 parts shown in Fig. 2, in partial section; and Fig. 4 a fragmentary section of the flushing valve.

In the drawings 10 indicates a tank having suitable storage capacity and provided 20 with a water inlet-nozzle of any desired construction which, in the drawings, is of a special form which is the subject matter of my above-mentioned application.

Leading from the tank 10 is a discharge 25 fitting 29 to which the discharge pipe 30 is attached. Fitting 29 is, in the main, quite similar to ordinary discharge fittings, being provided at its upper end with a valve seat 31. However, in my construction the throat 30 of fitting 29 is transversed by cross bar 32 carrying an upwardly projecting guide pin 33 which serves as a guide for my improved combined flushing valve and over-flow. This improved element comprises an over- 35 flow pipe 35 and a flexible valve ring 36, the pipe 35 having a length sufficient to project above the normal water level desired within the tank 10, and the ring 36 serving to rest upon valve seat 31 and thereby obstructing outflow through fitting 29.

In order to hold ring 36 in place under such conditions as to properly cooperate with seat 31, I provide the lower end of the overflow pipe 35 with a threaded ring 37 having a circumferential flange 38 provided with a slightly thickened shoulder 39 at its junction with the main body of the ring 37. By this construction the outer portion of ring 36, when it contacts with seat 31, is 45 free from contact with ring 38 so that the head of water in the tank may act upon ring 36 and hold it on its seat when the parts are in the positions shown in Fig. 4. A threaded ring 40 screws upon ring 37 so as to hold the packing ring 36 in place, and is

provided with a diametrical bridge bar 41 which is medially perforated at 42 to slip over guide pin 33 and thus serve as a guide for the lower end of tube 35.

Outflow from tank 10 is controlled by upward and downward movement of tube 35 and for this purpose I provide an operating arm 50 at one end hooked into enlarged substantially triangular openings in the upper end of tube 35 and at the other end carried by a stud 51 journaled in the lower end of a lever 52 pivoted on a pin 53 carried by a bracket 54 which is provided with a threaded stud 55 projectable through the wall of tank 10 and receiving a clamping nut 56.

Stud 55 is bored to receive an operating shaft 57 provided at its outer end with an operating handle 58 and at its inner end with a cam 59 adapted to engage a pin 60 on lever 52, the arrangement being such that, by rocking handle 58 in either direction from a normal position, cam 59 will act upon pin 60 to swing lever 52 to raise tube 35 and thus raise valve ring 36 from seat 31.

In order that valve ring 36 may be held away from seat 31 a sufficient length of time and automatically permitted to return at the end of such time, bracket 54 is provided with a dash-pot 62 and a dash-pot piston 63 is mounted therein and connected to lever 52, the arrangement being such that opening movement of lever 52 is substantially unrestricted and return movement is controllably resisted by the usual valve 64.

At the bottom of the dash pot 62 I provide a small by-pass 64^a which permits a rapid escape of the air past the piston 63 when the piston nears the limit of its stroke, thereby permitting pipe 35 to seat without restriction.

In order that piston 63 may not be accidentally withdrawn from the dash-pot 62, said dash-pot is separably secured to bracket 54 by means of flange 66 and screw 67, a portion 68 of the bracket projecting over the open end of the dash-pot, when the parts are assembled, so as to obstruct withdrawing movement of the piston 63.

I claim as my invention:

1. The combination, with a tubular flushing valve extending above the normal water level, of a manipulator comprising a bracket, an operating lever pivoted on said bracket, a manipulator shaft journaled in said bracket,

a cam carried by said shaft and acting upon the lever to swing said lever in one direction by movement of the shaft in either direction from neutral, a dash pot secured to the 5 bracket, and a piston mounted in said dash pot and connected to said lever.

2. A flushing valve manipulator comprising a bracket, and operating lever pivoted on said bracket, a manipulating shaft journaled in said bracket, a cam carried by said shaft and acting upon the lever to swing said lever in one direction by movement of the shaft in either direction from the neutral position a dash-pot secured to the bracket, 10 and a piston mounted in said dash-pot and connected to said lever.

3. A flushing valve manipulator comprising a bracket, an operating lever pivoted on said bracket, a manipulating shaft journaled in said bracket, a cam carried by said shaft and acting upon the lever to swing said lever in one direction by movement of the shaft in either direction from a neutral position, a dash-pot detachably secured to the bracket 20 and having its mouth partially obstructed by a portion of the bracket, a piston mounted in said dash-pot and connected to said lever.

In witness whereof, I have hereunto set my hand at Indianapolis, Indiana, this 10th day of November, A. D. 1925.

CHARLES A. WULF.
